(57) **CLAIM**

The ornamental design for a molded bottle juicer, as shown and described.

DESCRIPTION

FIG. 1 is a front top perspective view of the present invention molded bottle juicer;

FIG. 2 is a bottom plan view of the invention;

FIG. 3 is a top plan view of the invention;

FIG. 4 is a left side elevational view of the invention;

FIG. 5 is a right side elevational view of the invention;

FIG. 6 is a front elevational view of the invention; and,

FIG. 7 is a rear elevational view of the invention.
